(57) CLAIM

The ornamental design for a swaddling sleep sack, as shown and described.

DESCRIPTION

FIG. 1 is a front view of a first embodiment of a swaddling sleep sack;

FIG. 2 is a back view of the swaddling sleep sack of FIG. 1; FIG. 3 is a first side view of the swaddling sleep sack of FIG. 1;

FIG. 4 is a second side view of the swaddling sleep sack of FIG. 1;

FIG. 5 is top view of the swaddling sleep sack of FIG. 1; FIG. 6 is bottom view of the swaddling sleep sack of FIG. 1;

FIG. 7 is a perspective front view of the swaddling sleep sack of FIG. 1 in an open configuration;

FIG. 8 is a front view of the swaddling sleep sack of FIG. 1 with an infant;

FIG. 9 is a front view of a second embodiment of a swaddling sleep sack;

FIG. 10 is a back view of the swaddling sleep sack of FIG. 9;

FIG. 11 is a first side view of the swaddling sleep sack of FIG. 9;

FIG. 12 is a second side view of the swaddling sleep sack of FIG. 9; and

FIG. 13 is top view of the swaddling sleep sack of FIG. 9; FIG. 14 is bottom view of the swaddling sleep sack of FIG. 9;

FIG. 15 is a perspective front view of the swaddling sleep sack of FIG. 9 in an open configuration; and,

FIG. 16 is a front view of the swaddling sleep sack of FIG. 9 with an infant.

The broken lines illustrate portions of the swaddling sleep sack which form no part of the claimed design. The broken lines illustrate the infant in FIGS. **8** and **16** which forms no part of the claimed design.
